UNITED STATES PATENT OFFICE.

ROBERT L. DORAN, OF CHICAGO, ILLINOIS.

GAS GENERATOR AND LAMP.

No. 921,093.

Specification of Letters Patent. Patented May 11, 1909.

Application filed May 7, 1906. Serial No. 315,574.

To all whom it may concern:

Be it known that I, ROBERT L. DORAN, a citizen of the United States of America, and a resident of Chicago, in the county of Cook 5 and State of Illinois, have invented certain new and useful Improvements in Gas Generators and Lamps, of which the following is a specification.

The main object of my invention is to provide an improved gas generator and lamp in which an inverted mantle is used to throw the light downward and outward without obstruction, so as to produce a shadowless light which can be made portable and readily 15 set up or attached in places where an incandescent light is wanted and which are not provided with the ordinary gas or electric light fixtures. This object is accomplished by the device shown in the accompanying 20 drawings, in which:

Figure 1 is a vertical section of a generator and lamp constructed according to this invention. Fig. 2 is an enlarged vertical section of the lower end of the generator. Fig. 25 3 shows a vertical section of the needle valve 8 which controls the supply of fuel to the vaporizer.

In the form shown, the casing 1 has an air tube 2 extending horizontally through the 30 same. Said tube 2 has the upper interiorly threaded extension 3 having threaded therein the gas tip 4 which has the discharge orifice 5. A layer of gauze 6 extends across said tip at the lower end of the generator 35 pipe or chamber 7 which is threaded into said gas tip 4. The generator chamber or vaporizing tube 7 has a needle valve or shut-off valve 8 at its upper part. The canopy 9 has the perforated side walls 10 and rests loosely 40 in the flared part 11 of the casing 1. The perforated wall 10 has an aperture 12 therein of sufficient size to permit alcohol to be injected through a tube into the asbestos-retaining cup 13 or starter-lamp. Said cup 13 45 is made in the form of an annular trough surrounding the lower end of the generator chamber 7 above the air tube 2. Within the tube 2 is a slide valve 14 for shutting off the discharge of gas from the orifice 5. The gas 50 tube 15 is connected to and extends downwardly from the air tube 2 and has threaded thereto an extension 16 from which is suspended the mantle 17. Said mantle is attached to the ring 18 which connects by 55 means of arms 19 with the cap 20. Said cap is perforated at 21, and is attached to the

tube 16 by means of a pin 22 on said tube engaging in the slot 23 of said cap. The casing 1 is perforated near its lower part at 24, and is provided with screws 25 for engaging 60 the flange 26 of the globe 27.

The operation of the device shown is as follows: Gasolene is injected into the generator chamber 7, under pressure, through the usual wire-feed, and the flow into said chamber is controlled by the valve 8. Before the valve 8 is opened so as to permit the flow of gasolene or other gas forming liquid into the chamber 7, the asbestos 28 contained in the cup 13 will be soaked with sufficient alcohol 65 to heat the generator. This may be ignited either through the orifice 12 or by lifting the canopy 9. When the chamber 7 is sufficiently heated, the valve 8 is opened. The gas generated in the chamber 7 passes 70 through the orifice 5 and down into the tube 15 in the direction of the arrows, then through the mantle 17, and upwardly within the casing 1, around the air tube 2 and is there ignited by the flame at the cup 13. 80 This causes the ignition of the gas at the mantle 17 in the usual manner. The heat in the upper part of the casing 1 causes an upward draft of air in the casing. This draws the air into the tube 2, where it mixes with 85 the gas and passes down through the tube 15 and through the mantle. The tubes 2 and 15 together with the gas tip 6 form a Bunsen burner which provides sufficient air to heat the mantle to incandescence. To shut off 90 the gas and light, the valve 8 is closed and the slide valve 14 is pushed inwardly to close the orifice 5. The closing of the valve 14 shuts off the gas so as to immediately extinguish the flame. If the valve 14 should 95 be left open, the small quantity of gas passing from the generator chamber 7 would cause the mantle to burn red and to blacken in parts while said gas is being exhausted from the generator. The generator being directly 100 above and within the heating zone of the mantle, continues the generation of gas so long as the valves 8 and 14 are open, and while the gas is burning at the mantle.

Since the mantle, mixing tube, and generating or vaporizing tube are all in the same vertical line and co-axial with each other, and since the casing is co-axial with all of said parts, a great efficiency is obtained both in heating the generator and in preheating 105 the gas as it passes down through the mixing tube. The casing guides the heated air 110

from the burner vertically along the mixing and vaporizing tubes, and distributes the same equally upon all sides of said tubes.

The advantage of having the casing removably secured to the vaporizing tube, and having all of the other parts of the lamp secured to and suspended within the casing, is that the casing and attached parts of the lamp may thus be taken down for the purpose of cleaning or repair without detaching the vaporizing tube from its connection with the reservoir for the hydro-carbon liquid.

What I claim as my invention and desire to secure by Letters Patent is:

15. 1. A gas lamp and generator comprising a vertical vaporizing tube, a Bunsen burner suspended below and in vertical line with said vaporizing tube and communicating therewith, an inverted mantle suspended from and surrounding the lower end of said Bunsen burner and being in the vertical line of said vaporizing tube, and a casing surrounding said vaporizing tube and Bunsen burner and adapted to conduct the heat from 25 said mantle vertically along said vaporizing tube.

2. A gas lamp and generator comprising a vertical vaporizing tube having at its upper end a valve-controlled liquid inlet, and at its 30 lower end a valve-controlled gas outlet, a vertical gas mixing tube extending downwardly from said vaporizing tube in vertical line therewith, and having its upper end open so as to admit air from outside of said vaporizing tube, and a mantle surrounding the lower end of said gas tube, and being in the vertical line of said vaporizing tube.

3. A gas lamp and generator comprising a vertical vaporizing tube having at its upper 40 end a valve-controlled liquid inlet, and at its lower end a valve-controlled gas outlet, a vertical gas mixing tube extending down-

wardly from said vaporizing tube and co-axial therewith, an inverted mantle surrounding the lower end of said mixing tube and co-axial therewith, a casing surrounding said tubes and mantle, concentric therewith, and adapted to convey the heat from said mantle upwardly along the vaporizing tube, and an air inlet leading from the outside of the casing into said mixing tube.

4. A gas generator and lamp, comprising in combination a vertical vaporizing tube, an air inlet below the end thereof, a burner tube in axial alinement with said vaporizing tube, an inverted mantle depending from the lower end of said burner tube in axial alinement therewith, and a casing surrounding said tubes and adapted to conduct heated air from said burner and mantle along said vaporizing tube, said vaporizing tube being provided with means for regulating the flow of liquid fuel into its upper end and means for regulating the discharge of gas from its lower end.

5. A gas lamp and generator comprising a vertical vaporizing tube, a Bunsen burner suspended below and in vertical line with said vaporizing tube and communicating therewith, an inverted mantle suspended from and surrounding the lower end of said Bunsen burner and being in the vertical line of said vaporizing tube, and means at the top of said vaporizing tube adapted to introduce liquid fuel into said tube in minute quantities adapted for immediate vaporization by the heat rising from said mantle.

Signed at Chicago this 5th day of May 1906.

ROBERT L. DORAN.
